BY Emil F. Lange
ATTORNEY

UNITED STATES PATENT OFFICE.

RODNEY H. YALE, OF LINCOLN, NEBRASKA, ASSIGNOR TO REXFORD W. YALE, OF LINCOLN, NEBRASKA.

LUBRICATOR.

Application filed August 23, 1923. Serial No. 658,962.

To all whom it may concern:

Be it known that I, RODNEY H. YALE, a citizen of the United States, residing at Lincoln, in the county of Lancaster and State 5 of Nebraska, have invented certain new and useful Improvements in Lubricators, of which the following is a specification.

This invention relates to certain improvements in methods of lubrication for journal 10 boxes and journals of railroad and railway cars, locomotives, street cars and other vehicles and machines. The objects and nature of the invention will be readily understood by those skilled in the art in the light of the 15 following explanation of the accompanying drawings illustrating what I now believe to be the preferred mechanical expression or embodiment of my invention from among other forms, constructions, and arrangements 20 within the spirit and scope thereof.

One object of my invention is the provision of means for containing and carrying a supply of grease (non-fluid lubricant) in sufficient quantity for positively and automatically feeding a continuous supply of the lubricant to the bearing over a long period of time without the necessity of inspection, adjustment, or refilling, and without the use of waste or other absorbent 30 material; the lubricant being so positioned that it will be in contact with the moving member and its bearing and so arranged that it will be fed thereto by and on account of the jolting or vibration of the vehicle 35 or machine of which the moving member and bearing are parts.

It is a further object of my invention to provide a method and means for lubricating bearings without the use of waste or other 40 absorbent material, the direct application of the lubricant obviating fires in hot boxes and the carrying of grit and metal particles into the bearings.

Still another object of my invention is 45 the provision of a device of this character which will be simple in construction, efficient in practice, and economical in manufacture, and which is so designed that it can be quickly and easily attached without altering or remodeling parts now in use.

With these and other objects in view, in 50 whole or in part, the invention resides in and consists of certain novel features in con-

struction, or in combinations and arrangements as more fully and particularly set forth and specified hereinafter.

Referring now to the accompanying drawings which are part of my application:—

Figure 1 is a view in perspective of a journal box for a railway car, the journal 60 box being fitted with a lubricator embodying my invention.

Figure 2 is a section taken on the line 2—2 of Figure 3.

Figure 3 is a vertical longitudinal sectional view showing a railway car journal box equipped with a lubricator embodying my invention, and showing also a dust guard fitted with a grease retaining packing ring.

Figure 4 is a side elevation of a portion 70 of a railway car journal with the dust guard and packing ring, the dust guard and packing ring being shown in section.

Figure 5 is an elevation of the clamping arrangement for securing the lubricator to 75 the journal box.

Figure 6 is a section on the line 6—6 of Figure 5.

In the particular example illustrated for purposes of explanation, I have shown an ordinary, common journal box for a railway car journal, which will be familiar, together with its use and operation, to those skilled in the art.

It is not deemed necessary to show the 85 railway car or more than a fragmentary portion of the car axle to adequately illustrate and describe my invention and its application, as it is adaptable to any journal box or journal bearing, or other bearing for 90 any kind of moving part where there is sufficient vibration or jolting of the parts to cause the supply of lubricant to be fed automatically to the bearing.

The lubricant reservoir 10 is formed with 95 imperforate walls 11, which are preferably flared or enlarged outwardly and upwardly from the mouth 12 of the journal box to substantially the line 2—2 as indicated in Figure 3. The upper portions of the sides 100 11 converge toward the mouth or opening 13, which in my preferred construction has the same size and dimensions as the opening 12 of the journal box. Adjacent the opening 13 the wall 11 is provided with lugs 15 105 which are similar to the lugs 16 of the jour-

nal box 17, these lugs being so positioned that the lid 14 and the spring 18 will function in the same manner as when the lid is hinged to the lugs 16.

5 This construction enables me to provide a lubricant container of large capacity, and so constructed and proportioned that it will not interfere in any way with the working parts of the car truck, at the same time 10 leaving the lid free from interference when it is desired to raise or to lower the lid. It will also be noted that no alterations whatever are required in the construction of the journal boxes already in use on railway 15 cars. It is only necessary to remove the lid from the journal box, to secure my lubricant reservoir to the journal box in the manner shown in Figures 1 and 3, and then to secure the lid to cover the mouth 13. It 20 is my desire however that the illustrations and description explain the convenient and economical adaptability of my invention to any of the journal boxes in common use on railway cars, locomotives and other vehicles 25 and machines. It is not my desire however to restrict myself to the precise form of my invention shown in the drawings, nor to convey the impression that the invention is adaptable only to the particular type 30 of journal box and lid illustrated, these particular types being shown merely for convenience and by way of illustration.

The lubricant container 10 may be secured to the journal box in any desired 35 manner, as for example by means of the clamp arrangement shown in Figures 5 and 6. The clamp consists of two parts 19 and having their lower edges directed inwardly as shown in Figures 3 and 6. The parts 40 19 are provided with ears 20 as shown in Figure 5 whereby the parts 19 may be secured together by means of bolts 21 or other suitable fastening devices. This clamp arrangement affords a convenient 45 device for securing the lubricant container to the journal box to cover its opening 12 after the lid 14 has been removed therefrom. The flange 22 on the lubricator 50 reservoir 10 and the lip 23 surrounding the opening 12 of the journal box 17 provide secure holding surface for the clamp 19, which as will be seen by reference to Figures 3 and 6, is formed to closely fit the flange 22 and the lip 23.

55 I also show a dust guard or lubricant retainer, this being shown in its relation to the journal box in Figure 3 and separately shown in enlarged detail in Figure 4. This comprises two wood pieces 24 60 having in this instance the same dimensions in their outer measurements as the usual wooden dust guard of railway car journals. A pair of such pieces 24 is provided with registering apertures through which bolts 65 26 or other suitable fastening devices may

be passed as shown in Figure 4. The pair of pieces 24 is so formed as to enclose and tightly engage a felt ring 25 which is formed with converging and inclined sides against which the wood parts are compressed when the screw threaded bolts 26 are tightened, this action tending to cause the felt ring 25 to fit closely against the car axle 27 and to thus prevent the escape 70 of lubricant and the entrance of dust.

75 In the application and use of my invention in connection with such a bearing as I have illustrated for the purpose of explanation, the journal box 17 and lubricant reservoir 10 are filled with grease of light 80 or moderate consistency, non-fluid, but not a so called heavy thick grease. The consistency should be similar to that of the grease generally used in automobiles and commonly termed "light" or "moderate" 85 cup grease. Such grease is made by many manufacturers of lubricants, and its consistency is intended to and does remain substantially the same in warm and cold weather.

90 In the journal box 17 and other parts shown in my illustrations, the journal 28 rotates in the bearing 29, which lies in contact with the wedge 30. As the car or locomotive moves on its road in ordinary use, the journal rotates in its bearing and a certain vibration or jolting results from the movement on the roadway. This jolting, 95 vibration and vibration causes the lubricant to be automatically fed to the bearing as long as there is a supply of lubricant 100 in the reservoir or journal box.

One of the principal and primary objects of this invention is the provision of 105 an economical method of applying a large supply of lubricant, sufficient for automatically and continuously lubricating the bearing over a long period of time, the method being applicable to the present common type of journal box generally used on 110 railway cars of many kinds, and on other rolling stock, without changing or replacing the present equipment or installation. The method further contemplates the doing away with the use of fluid oil and of waste 115 or other absorbent material which is the principal cause of fires in hot boxes, resulting in loss of time through delays and in the loss of material occasioned by the necessity of the replacement of burned out 120 parts.

125 My device is also readily adaptable to designs and types of bearings for moving parts other than the type of journal box shown in my drawings. For instance, should new designs of railway journal boxes be constructed for especial use with my invention, it would be advantageous from the standpoint of economy to materially reduce the space between the journal and the bot- 130

tom of the journal box, since the usual, common, present day journal box was originally designed to be filled with waste. Since I do away entirely with the use of 5 waste, it is not necessary to provide space for waste in the journal box.

This invention is an improvement in the method of and means for lubricating any bearing of a moving part of any vehicle or 10 machine where there is sufficient vibration to cause the grease supply to feed the bearing, as the large supply of lubricant provided will under such conditions feed automatically and continuously to the bearing 15 over a long period of time (several weeks or months), without the necessity of inspection, attention, or recharging. The lubricant supplied to the bearing will be free from grit and from particles of metal that may be de- 20 tached from time to time by the action of the parts. The tendency of grit and metal particles is to sink to the bottom. If fluid or fluent lubricant is used either with or without waste, these substances reach the bear- 25 ings through the waste as a medium or through the churning of the liquid lubricant. With my invention however, these sub- 30 stances remain at the bottom of the journal box, since there is no medium through which they can travel upwardly toward the bearing.

This invention has particular and special merit when applied to journal boxes for rail- 35 way cars. The necessity for frequent in- spection and recharging, as now required by the present general practice of lubricating with fluid oil and waste, is avoided in the use of my invention. There is also a very ma- 40 terial saving of the cost of the waste, as well as in the cost of the oil which works out or 45 is otherwise wasted at present. My inven- tion also avoids the burning out of bearings, thus saving not only the cost of the bearings but saving also the labor costs of the replace- 50 ment of the bearings. Another advantage of my invention over present practices is the entire avoidance of hot boxes with the at- tendant delays, inconvenience, and expense incidental thereto.

55 In the present system of lubricating rail- way car journals, insufficient attention is given in many instances to the exclusion of dust from the rear side of the journal box, and it is well known that dust entering the journal box injures the quality of the lubri- 60 cant and tends to injure the bearings. In my invention the dust is excluded from the journal box by the dust guard and lubricant retainer.

65 It is evident that various changes, varia- tions, and modifications might be resorted to without departing from the spirit and scope of my invention and hence I do not

wish to limit myself to the exact disclosures hereof. 65

Having thus described my invention in terms which will be readily understood by others skilled in the art to which it pertains, and desiring to protect it in the broadest manner legally possible, what I believe to 70 be new and desire to secure by Letters Patent of the United States is:—

1. In combination, a moving part and a bearing therefor, a lubricant box adapted to hold a supply of grease sufficient for 75 properly lubricating said moving part and its bearing for a comparatively long period of time while in normal service and having a convenient opening for refilling with lubri- 80 cant, said box confining the grease in a man- ner to keep it in contact with said part and bearing while in normal operation, the body portion of said box having an enlargement of greater area in cross section than the area of the refilling opening, a portion of the in- 85 terior of said box sloping toward its bottom to, permit the grease to slide downwardly when aided by the normal vibration of the machine of which the said moving part and bearing are members. 90

2. In combination, a machine, a journal, a journal box and bearing therefor, an en- 95 larged normally closed part of the journal box extending upwardly and laterally from the bearing to hold a comparatively large supply of non-fluid lubricant for long con- 100 tinuous self lubrication, two or more of the sloping interior walls of the enlarged part acting as a retardant to the free downward movement of the lubricant toward the bearing unless aided by the vibration of said parts due to the normal operation of the machine.

3. In combination, a journal box for rail- 105 way cars and similar vehicles, the journal and its bearings, a container having two or more of its sides enlarged laterally from said bearings and adapted to confine a reserve supply of non-fluid or grease lubricant in 110 contact with said bearing, the position and form of said container being such that the vibration or jarring of the container is re- 115 quired to cause the lubricant to feed toward and to the bearing.

4. In combination, a journal, a bearing and supporting elements therefor, a con- 120 tainer having its middle portion enlarged on two or more of its sides and adapted to confine a relatively large store of non-fluid lubricant in communication with said jour- 125 nal and bearing and so positioned that it will supply the journal and bearing with new lubricant when vibrated or jarred.

In testimony whereof I affix my signa- 130 ture.

RODNEY H. YALE.
